ELECTRODE HOLDER

Lawrence O. Green, Cincinnati, Ohio, assignor to
The Foster Transformer Company, Cincinnati,
Ohio, a corporation of Ohio

Application November 4, 1949, Serial No. 5,859

Term of patent 14 years

(Cl. D26—1)

To all whom it may concern:

Be it known that I, Lawrence O. Green, a citizen of the United States of America, residing at Cincinnati, in the county of Hamilton and State of Ohio, have invented a new, original, and ornamental Design for an Electrode Holder, of which the following is a specification, reference being had to the accompanying drawing, forming a part hereof, in which:

Figure 1 is a top plan view of an electrode holder, showing my new design.

Figure 2 is an elevational view thereof.

Figure 3 is a bottom plan view thereof.

Figure 4 is an end elevational view thereof as seen from the left of Figure 2, and

Figure 5 is an end elevational view thereof as seen on the line 5—5 of Figure 2.

The dominant features of my design reside in that portion of the drawing shown in full lines.

I claim:

The ornamental design for an electrode holder, substantially as shown and described.

LAWRENCE O. GREEN.
